(57) **CLAIM**

The ornamental design for a fan assembly, as shown and described.

DESCRIPTION

FIG. 1 is a front, bottom perspective view of a fan assembly showing our new design;

FIG. 2 is a rear elevational view showing the design for the fan assembly of FIG. 1;

FIG. 3 is front, top perspective view showing the design for the fan assembly of FIG. 1;

FIG. 4 is a bottom plan view showing the design for the fan assembly of FIG. 1; and,

FIG. 5 is a top plan view showing the design for the fan assembly of FIG. 1.

In FIGS. 1–5, the broken line showing of various items including (i) the central vertical support member (FIGS. 1–3 and 5), (ii) a portion of the ceiling to which the central vertical support member is attached (FIG. 1), (iii) the upper motor housing portion (FIGS. 1–3 and 5), and (iv) the light cover located below the lower motor housing portion (FIGS. 1–4) is for illustrative purposes only and forms no part of the claimed design.
